UNITED STATES PATENT OFFICE.

HUGH D. MACPHERSON, OF SUMMIT, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed January 5, 1922. Serial No. 527,072.

To all whom it may concern:

Be it known that I, HUGH D. MACPHERSON, a citizen of the United States, residing at Summit, in the county of Union, State of New Jersey, have invented certain new and useful Improvements in Telephone Systems, of which the following is a full, clear, concise, and exact description.

This invention relates to improvements in telephone systems and has particular reference to a system wherein signals for a plurality of toll lines extending between widely separated offices are transmitted over a signalling path common to said toll lines.

The present invention contemplates a toll switching system wherein connections are extended from one terminating office to another over sectionalized toll lines which are joined to an intermediate office to which calls may also be extended from either of the terminating offices. In a system of this character it is desirable, when any one of the plurality of toll lines interconnecting the terminating and intermediate offices is taken for use, to indicate the busy condition of such line at the various offices.

An object of the invention is to transmit code impulses over a common path for operating certain signals to indicate at distant offices the busy condition of the toll line taken for use and also for operating a signal individual to said line before an operator at the office which is called.

Another object is to selectively signal a particular one of a plurality of operators at either terminating office over any one of said toll lines and to operate at the terminating and intermediate offices the busy signals of the line taken for use. A further object is the provision of a plurality of signals for each toll line at certain offices which are selectively operable by codes of transmitted impulses having different characteristics which are determined by the cooperation of selective switches, said codes being individual to the particular line taken for use.

These and other objects of the invention not specifically mentioned above will clearly appear from the following description and drawings, Figs. 1 to 8 of which, when arranged in accordance with Fig. 9, illustrate a preferred embodiment of the invention.

In carrying out the invention each toll line of a group is preferably provided at each terminating office with a plurality of terminals or jacks, certain of which are employed for outgoing traffic, while others are utilized for incoming traffic. For outgoing traffic, the originating operator has access to three jacks for each line, two of which are employed for calling the distant terminating office, while the remaining one is used when signaling the operator at the intermediate office. If the call is an original one to be extended to the distant terminating office, the operator at the calling office inserts the plug of a cord circuit into what is designated as the outward "in" jack on the drawings (Figs. 1 and 7). This causes the transmission of current impulses over a path common to the toll lines of a group and joining the calling office with the intermediate and distant terminating offices. This code of impulses is individual to the line taken for use and the particular operator at the terminating office with whom it is desired to establish connection. Current impulses are transmitted and received by means of start-stop distributors, and upon being received at the intermediate office are translated, in a well-known manner, to effect the operation of signals at the intermediate office which indicate thereat the busy condition of the toll line which has been taken for use. The impulses are repeated at the intermediate office and transmitted to the called terminating office and upon being received thereat are again translated to actuate certain mechanism which controls the operation of a line signal associated with the inward "in" jack.

Under certain traffic conditions to be later explained in detail, it is necessary that the line signal individual to the line taken for use and to the inward "out" jack at a terminating office be operated. In this event a plug is inserted in the outward "out" jack at one terminating office, whereupon a code of impulses individual to the line taken for use and to the inward "out" jack at the other terminating office is transmitted over the common signalling path to again operate the busy signals at the intermediate office, where the code is again repeated and transmitted to the last-named terminating office to effect the operation of the line signal thereat individual to the line taken for use and the in-

ward "out" jack, and also to operate the busy signals for the line at the last-mentioned terminating office.

When calling the intermediate office from either terminating office, the operator connects a cord circuit to the outward "through" jack. The signal before the "through" operator at the intermediate office individual to the line taken for use, together with the busy signals for said line at said office, are thereupon operated by a code of impulses transmitted from the originating office. This code is repeated at the intermediate office and transmitted to the other terminating office to cause the operation of busy signals at the latter office individual to the seized line.

In order to accomplish the signaling of the various positions indicated by the jacks at the terminating and intermediate offices, each toll line has three sets of code impulses individual thereto, one each for the line signals assigned to the inward "in" and "out" jacks at the terminating offices and the jacks at the intermediate office. To produce these various code signals the present invention preferably makes use of four rotary switches (see Figs. 2 and 6) associated with each sending distributor employed, all of these switches being common to a group of toll lines. Each one of three of said switches is individual to one of the positions to be called, while the fourth switch is common to said positions. When a call is initiated on any particular line of the group served by said switches, the wipers of the first three mentioned switches are operated to select the terminals of their banks individual to the seized line, whereupon the fourth switch is actuated to step its wipers to terminals individual to the position being called. Then through the wipers of the switch of the first three mentioned which is individual to the position called, and through the wipers of the fourth switch, certain battery potentials which determine the code of impulses to be transmitted are connected to the sending segments of the start-stop distributor.

It is believed that the invention will now be fully understood from the following detailed description of the various operations in establishing and disconnecting calls between the different offices.

Operator at office X initiates a call to office Z.

When the toll operator at office X desires to establish a connection to the inward operator at office Z, the plug 100 of an operator's cord circuit A is inserted into the "in" jack 101 of the outward jacks associated with an idle toll line L. The cord circuit A may be of a type well known in the art and only so much of this circuit is shown as is necessary to an understanding of the operation

of this system. It is understood that this cord circuit is employed to connect the toll operator with the calling subscriber and afterwards to complete the connection between the calling and called subscribers over the toll line L. The connection of the cord circuit A with the toll line L is designed to transmit a code of impulses from the office X through the intermediate or through office Y to the terminating office Z, which code of impulses results in the operation of signals at the intermediate or through office to indicate the busy condition of the line L which has been selected and to also operate a signal before the incoming operator at office Z to indicate that a call is awaiting attention on the line L. The insertion of plug 100 into the "in" jack 101 establishes a circuit extending from ground through the winding of the sleeve relay 102 of the cord circuit A, the sleeve contacts of the plug 100 and jack 101, the winding of relay 103 individual to the jack 101, and the left-hand winding of the common relay 104 to grounded battery. Relays 103 and 104 energize in this circuit and the closure of the alternate contact of relay 103 establishes an obvious energizing circuit through the right-hand winding of relay 105. When relay 105 is energized relay 104 is locked in a circuit extending from grounded battery through the right-hand winding and alternate contact of relay 104, and the inner right-hand alternate contact of relay 105 to ground. The operation of relay 105 also establishes a circuit for operating the busy signal magnets 118, 119 and 120 to indicate the busy condition of the line L, said circuit extending from grounded battery through the magnets 118, 119 and 120 in series, and the inner right-hand contact of relay 105 to ground. Slow release relay 126 is also energized at this time over a path extending from grounded battery through the winding of relay 126, the normal contact of relay 129 and from thence over the locking circuit of relay 104. The operation of relay 126 performs no function at this time.

The calling operator now depresses her ringing key 140 in the cord circuit A, and in response to the connection of the ringing current to the toll line L the ringing relay 106, bridged across the line L, is operated. A circuit is thereupon established for the slow-to-release relay 107 extending from grounded battery through the winding of this relay and the contact of relay 106 to ground. The operation of relay 107 closes an energizing circuit for relay 108 extending from grounded battery through the right-hand normal contact of relay 109, the winding of relay 108, and the alternate contact of relay 107 to ground. Relay 108 energizes and locks through its inner left-hand

alternate contact. The closure of the inner right-hand alternate contact of relay 108 establishes an obvious energizing circuit for slow-to-release relay 110, which, in operating, locks through its inner left-hand alternate contact to ground at the left-hand normal contact of relay 111. When the outer right-hand contact of relay 108 is closed ground is extended through the right-hand normal contact of relay 111 to the outer right-hand contact of relay 107, which relay is now energized. The closure of the outer left-hand contact of relay 108 connects ground to the inner right-hand armature of relay 107. When the operator releases the ringing key, relay 106 deenergizes to open the energizing circuit for relay 107, which, after an interval, restores. The opening of the alternate contact of relay 107 breaks the original energizing circuit for relay 108, but this relay remains locked through its inner left-hand contact. The closure of the inner right-hand contact of relay 107 connects ground to the start conductor 112 which extends to the contact of relay 200 and from thence in multiple through the normal contacts of relays 201, 202 and 203 to the contacts and windings of the motor magnets 204, 205 and 206, respectively, of the rotary switches B, C and D. The ground connected to the outer right-hand contact of relay 107, by the closure of the outer right-hand contact of relay 108, is extended, when relay 107 releases, through the outer right-hand contact of relay 105, which is now energized and locked through its left-hand winding and inner left-hand contact to the outer left-hand contact of relay 110, to the individual conductor 113 of the toll line L, which is connected to a terminal of the switch D over which the wiper 207 passes. It is to be noted that the other conductors 114 and 115, individual to the toll line L and connected, respectively, to terminals of the switches C and B, are not grounded since relays 116 and 117, similar to relay 105, are not operated. The conductors 113, 114 and 115 are connected, respectively, to corresponding terminals in the banks of switches D, C and B over which the wipers 207, 208 and 209 pass, and these corresponding terminals are each individual to the toll line L which has been selected for use, the other terminals of said banks being individual to other similar toll lines. When the start conductor 112 is grounded, as previously described, circuits are closed for the stepping magnets 204, 205 and 206 of the switches B, C and D, and the wipers of these switches are stepped over their associated terminals. This stepping action continues until the wiper 207 of switch D engages the terminal to which conductor 113 is connected. This conductor being now grounded, when wiper 207 engages said terminal the ground will be extended therethrough to the left-hand winding of relay 203 and from thence to grounded battery. Relay 203 energizes to permanently open the circuit of the stepping magnet 206. In closing its inner left-hand contact relay 203 establishes an energizing circuit for relay 200 which operates to disconnect the start conductor 112 from the windings of the various stepping magnets. These magnets now cease to operate and bring the wipers of the switches B, C and D to rest upon the associated terminals individual to the toll line L. The ground which is connected to the inner left-hand contact of relay 203 is also extended through the normal contact of relay 210 and the contact and winding of the stepping magnet 211 of the rotary switch E. The stepping magnet 211, therefore, operates and relay 203 is energized and steps the wipers of switch E until the wiper 212 engages a terminal to which ground is connected. In the present instance ground is connected through the wiper 207 and terminal engaged thereby, the right-hand contact of relay 203 to the first, fourth and seventh terminals of the row over which wiper 212 passes. Therefore, with the wiper 212 in the position shown in the drawing it will be apparent that the same will be caused to take only one step, whereupon the ground connected to the fourth terminal then engaged will be extended through the left-hand winding of relay 210 to grounded battery to energize this relay and open, at its left-hand contact, the circuit for the stepping magnet 211, which thereupon ceases to operate. The wipers of switch E are now brought to rest on terminals which are individual to the switch D, this latter switch being the one which controls the character of certain of the impulses of the code to be transmitted to the terminating office Z when the inward operator at said office is being called. In like manner the switches C and B control the character of certain of the impulses of the codes transmitted from the originating office when the outward operator at the terminating office or the through operator at the intermediate office is being called. With the wipers of switch E engaging terminals individual to the switch D, it will be obvious that only the polarities connected to the terminals engaged by the wipers 213, 214, 215, 216 and 217 of switch D will be effective in determining certain of the impulses of the code to be transmitted. The code transmitted in each instance consists of eight impulses seven of which are determined by the polarities connected to wipers 219 to 225 inclusive of the switch E, the eighth impulse being determined by the condition of the relay 243 associated with the sending distributor SD, which is of the usual start-stop type such as employed in printing telegraphy. The sending distributor

SD is connected to a receiving distributor RD at the intermediate or through office Y over a common signaling path or conductor P which terminates in the windings of polar 5 relays 250 and 450. In order that the transmitted code combinations may be translated into suitable signals for appropriate toll lines and the desired operator's position at the distant office, the invention preferably 10 provides a receiving apparatus associated with the receiving distributor RD which is selectively responsive to the transmitted code combinations to effect the operation of the proper signals. This receiving apparatus 15 thus, as herein shown at the intermediate station Y, includes a plurality of locking relays 400 to 407, the locking circuits of which are controlled by common relay 408. The apparatus further includes a pyramid relay 20 combination of a type well known in the signaling art, the relays of this combination being indicated by the numerals 409 to 432 inclusive. In accordance with the code of impulses transmitted, the apparatus, including 25 the locking and pyramid relays, responds to provide a path through contacts of said relays over which the signals individual to the selected toll line and operator's position are transmitted.

30 *Transmission of a code of impulses for line L individual to the "in" operator's position at office Z.*

The apparatus is now in condition to 35 transmit the code of impulses individual to the line L and to the "in" operator's position at office Z to the receiving mechanism at the intermediate office Y. With the brush 227 of the sending distributor SD in its normal 40 position a circuit is established, upon the energization of relay 210 as previously described, extending from grounded battery through the start magnet 228 of the sending distributor, the right-hand contact of relay 45 210, the start segment 229, the brush 227 and the ring 230 to ground. Magnet 228 energizes in this circuit to release brush 227, which thereupon makes a complete revolution. When brush 227 is disengaged from 50 the start segment 229 shortly after the beginning of its revolution, the circuit for the start magnet 228 is opened and this magnet releases to permit its armature to move into the path of the brush 227 so that when the 55 latter completes its revolution it is stopped by said armature. Upon engagement of brush 227 with segment 231 at the beginning of the revolution of the brush, a circuit is established from the positive pole of 60 battery through segment 231, brush 227, ring 232, and thence over one path through the lower winding of polar relay 250 and the artificial line to ground, and over another path through the upper winding of 65 relay 250, the common conductor P and both

windings of polar relay 450 to ground through the artificial line. The closure of this circuit has no effect upon the polar relay 250 but causes the relay 450 to close its lower contact, whereupon a circuit is established from grounded battery through the lower contact of relay 450, the segment 433 of the receiving distributor RD, brush 434 thereof, segment 435, and the winding of start magnet 436 to ground. The closure of this circuit energizes the magnet 436 to release brush 434, which thereupon makes a complete revolution in synchronism with the brush 227 of the sending distributor SD. The disengagement of the brush 434 from segments 433 and 435, at the beginning of the revolution of the brush opens the energizing circuit for magnet 436 which thereupon releases so that its armature will stop the brush 434 at the completion of the revolution. With the brushes of the sending and receiving distributors now revolving in synchronism, the code of impulses determined by the positions of the wipers of switches D and E is now transmitted.

After passing from engagement with the wipers 229 and 231, the brush 227 engages segment 233, thereby establishing a circuit extending from ground through the ring 230, brush 227, segment 233, and the right-hand winding of relay 210 to grounded battery. This circuit also extends in multiple through the wiper 218 and the fourth terminal in its associated row, and from thence through the right-hand winding of relay 203 to grounded battery. This circuit further extends in multiple through the wiper 234 of switch D, and through the winding of relay 109 to grounded battery. Relays 210 and 203 are maintained energized as long as brush 227 is in engagement with the segment 233, and relay 109 is energized in the circuit described therefor and remains energized contemporaneously with the relays 210 and 203. The energization of relay 109 opens, at its right-hand contact, the locking circuit for relay 108 and this relay thereupon restores. The release of relay 108 removes ground from the conductor 113 connected to the terminal now engaged by wiper 207 of switch D, thereby opening the original energizing circuit for relay 203, but this relay remains energized in the circuit through its right-hand winding. The release of relay 108 also removes ground from the start conductor 112 to prevent any further operation of the stepping magnets 204, 205 and 206 when relay 200 releases, which release occurs when the relay 203 deenergizes at the termination of the revolution of the brush 227, that is, when said brush disengages the segment 233.

At the same time that segment 233 is engaged by brush 227, segment 235 is also engaged and a circuit is thereupon established

extending from the negative pole of battery through the wiper 219 of switch E and fourth terminal engaged thereby, segment 235, brush 227, segment 232, the upper winding of polar relay 250, common conductor P, and the windings of polar relay 450 to ground. The impulse of negative polarity transmitted over the path P by the closure of this circuit operates the polar relay 450 to cause the same to close its upper contact. At the time that this impulse is transmitted brush 434 is in engagement with the segments 437 and 438, the latter segment being connected to the left-hand winding of the 15 first locking relay 400. The closure of the upper contact of relay 450 therefore establishes a circuit extending from grounded battery through the upper contact of relay 450, segment 437, brush 434, segment 438, and the left-hand winding of locking relay 400 to ground. Relay 400 operates and locks through its right-hand winding and left-hand contact to ground at the contact 20 of relay 408 which was energized over an obvious circuit when the brush arm 434 first engaged the segment 440. The brushes 227 and 434 next engage, respectively, the segments 236 and 439. A circuit for transmitting the second impulse of negative 25 polarity for the signaling conductor P is now established, said circuit extending from the negative pole of battery through wiper 213 of switch D and terminal engaged thereby, wiper 220 of switch E, segment 236, brush 227, segment 232, and from thence over the previously described path through the polar relays 250 and 450. This impulse of negative polarity maintains the upper contact of relay 450 closed whereupon a circuit 30 is established from grounded battery through said upper contact, segment 437, brush 434, segment 439, and the left-hand winding of relay 401 to ground. Relay 401 energizes and locks through its right-hand 35 winding and left-hand contact to ground at the contact of relay 408. The third impulse transmitted is of positive polarity and the circuit therefor is closed when brushes 227 and 434 engage, respectively, segments 237 and 441. The circuit for this impulse is 40 traceable from the positive pole of battery through the wiper 214 of switch D, the wiper 221 of switch E, segment 237, brush 227, segment 232, and from thence over the previously traced path through the polar 45 relays 250 and 450. Relay 450 operates to close its lower contact and hence no circuit will be established for the locking relay 402. The fourth impulse to be sent is of negative polarity and is transmitted over the common path P when the brushes 227 and 434 engage, respectively, segments 238 and 442. When this occurs current of negative polarity is connected through the wipers 215 and 222 of switches D and E and extended 50 through segments 238 and 232 and the polar relays 250 and 450. The relay 450 closes its upper contact in response to this impulse and thereby establishes an operating circuit for locking relay 403 extending from 55 grounded battery through the upper contact of relay 450, segment 437, brush 434, segment 442, and the left-hand winding of relay 403 to ground. Relay 403, in energizing, locks through its right-hand winding and left-hand contact to ground at the contact of relay 408. The fifth and sixth impulses transmitted are, respectively, of positive and negative polarities and are sent 60 when the brush 227 engages segments 239 and 240, at which time brush 434 engages segments 443 and 444. It is believed that the establishment of these circuits for the successive impulses will be clearly understood from the previous description. The fifth impulse being of positive polarity will fail to operate the locking relay 404. The sixth impulse of negative polarity causes the 65 operation of locking relay 405 and the locking of the same in a manner which is now believed to be obvious. The seventh impulse is determined by the position of the wiper 225 which is now in engagement with the fourth contact of its associated row, to which negative polarity is connected. This 70 seventh code impulse is transmitted when brushes 227 and 434 engage, respectively, segments 241 and 445. The character of this impulse causes polar relay 450 to close 75 its upper contact to establish an energizing circuit for locking relay 406, which, upon energizing, locks through its right-hand winding to the contact of relay 408. The eighth and last impulse is transmitted when brushes 227 and 434 engage, respectively, the segments 242 and 446. The circuit for this impulse extends from positive pole of battery through the normal contact of relay 243, segment 242, brush 227, segment 232, and from thence over the previously 80 described path. This impulse being of positive polarity prevents a circuit from being established for the locking relay 407. As a result of the code of impulses transmitted 85 locking relays 400, 401, 403, 405 and 406 have been operated and locked. 90

At the termination of the last impulse, brush 227 passes from engagement with the segment 233 and thereby disconnects the holding ground from the windings of relays 210, 203 and 109, which relays thereupon restore to normal. The release of relay 203 opens the holding circuit for relay 200 which thereupon releases. The apparatus is now 95 in normal condition with the exception of the operation of relays 103, 104, 105 and 110 and the busy signals 118, 119 and 120. 100

At the same time that the brush 227 disengages the segment 233, the same also disengages the segment 242 and then engages 105

110

115

120

125

130

the segment 244 to cause the transmission of a negative impulse over the path P, which operates relay 450 to close its upper contact. At this time the brush 434 has disengaged segments 437 and 446 and hence the closure of the upper contact of relay 450 will have no effect.

The result of the operation of the various locking relays will now be described. When the relay 400 operates, a circuit is established from ground through the right-hand contact of relay 400 and the windings of pyramid relays 427 to 432 inclusive, in series to grounded battery. These relays energize and are held operated as long as the relay 400 remains locked. The operation of relay 401 closes a circuit extending from ground through the right-hand contact of relay 401 and the windings of relays 420 to 426 inclusive, in series to grounded battery. These latter relays also energize. When relay 403 operates an obvious circuit is closed for energizing relays 412 to 415 inclusive. Relay 409 is also operated by the energization of the locking relay 405. With the pyramid relays described as energized in their operated condition and upon engagement of the brush 434 with segments 447 and 448, a circuit is established extending from the negative pole of 120 volt battery through the normal contact of relay 407, segment 447, brush 434, segment 448, right-hand alternate contacts of relays 406 and 409, left-hand normal contact of relay 411, left-hand alternate contact of relay 414, right-hand normal contact of relay 418, the right-hand alternate contact of relay 425, the left-hand alternate contact of relay 430, the conductor 449, and the left-hand winding of differential relay 500 to ground. This circuit energizes the relay 500 which then locks through its right-hand winding and contact. When relay 500 closes its outer left-hand alternate contact, the 120 volt impulse of current is transmitted to the right-hand winding of relay 507 causing this relay to energize. However, since no locking circuit for relay 507 is established at this time, the relay 508 being released, relay 507 releases at the termination of the impulse without performing any function. The energizing circuit for relay 500 is opened when the brush 434 passes from engagement with segments 447 and 448. At the same time, said brush disengages segment 440, whereupon the circuit for relay 408 is opened and this relay releases to open the locking circuits of the relays 400, 401, 403, 405 and 406, which relays thereupon restore. The restoration of these relays opens the circuits for the various pyramid relays which have been operated and these latter relays also release. The code of impulses individual to the line L and to the "in" operator's position at office Z

has now been transmitted to the intermediate or through office Y.

Upon the energization of relay 500 in response to the impulse of negative polarity transmitted over the conductor 449, a circuit is established for relay 504 extending from grounded battery through the right-hand winding of relay 504, the inner left-hand alternate contact of relay 500, and the outer normal contact of relay 509 to ground. Relay 504 energizes and thereby established a circuit to operate the busy signal magnets 320 and 520 to indicate, at the intermediate office Y, the busy condition of the toll line L, said circuit extending from grounded battery through the windings of magnets 320 and 520 in series, and the outer left-hand contact of relay 504 to ground. The energization of relay 504 also closes a circuit traceable from grounded battery through the right-hand contact of relay 516, winding of relay 517, the right-hand normal contact of relay 518, the outer right-hand contact of relay 504, and the outer normal contact of relay 509 to ground. Relay 517 energizes in this circuit and locks to ground through its winding and inner left-hand contact. The closure of the outer left-hand contact of relay 517 establishes an obvious energizing circuit for relay 519 which thereupon energizes and locks through its left-hand contact to ground at the left-hand normal contact of relay 521. The energization of relay 519 establishes a circuit extending from ground through the outer right-hand contact of relay 519, and from thence over one path through the normal contacts of relays 503 and 507 and winding of slow-to-release relay 508 to grounded battery, and over another path through the normal contacts of relays 303 and 307 to grounded battery through the winding of the slow-to-release relay 308. The relays 308 and 508 energize in this circuit but perform no functions at this time.

When relay 517 operates, ground is connected through the inner right-hand contact of this relay and the left-hand normal contact of slow-to-release relay 522 to start conductor 512, which is connected, through the contact of relay 600 and the left-hand normal contacts of relays 601, 602 and 603, to the windings of the stepping magnets 604, 605 and 606 of the switches B', C' and D'. The closure of the outer right-hand contact of relay 517 extends the ground connected to this contact through the right-hand normal contacts of relays 521 and 522, the inner right-hand contact of relay 504, and the individual conductor 513 to the terminal individual to the toll line over which the wiper 607 of switch D' passes. Stepping magnets 604, 605 and 606 operate upon the grounding of conductor 512 to step the wipers of their respective switches until the wiper 607 en-

gages the terminal in its row to which conductor 513 is connected. Relay 603 thereupon energizes to open the circuit for stepping magnet 606 and to close, at its left-hand alternate contact, an obvious energizing circuit for relay 600. This relay operating, breaks the continuity of the start conductor 512, whereupon stepping magnets 604 and 605 cease to operate and the wipers of switches B', C' and D' are thereupon brought to rest upon terminals individual to line L. A code of impulses is now transmitted from the office Y to the office Z and translated by the receiving mechanism of Fig. 8 to select the conductor 849. The operation in connection with the transmission of this code of impulses is precisely the same as that described in connection with the transmission and reception of the code of impulses from office X to office Y by the sending and receiving mechanisms of Figs. 2 and 4. Inasmuch as the mechanism of Figs. 2 and 6 and Figs. 4 and 8 are duplicates and the reference characters applied to like parts in duplicate figures are the same with the exception of the hundreds digits, it is believed that the operation of the transmission of the code of impulses from office Y to office Z will be fully understood by reference to the previous description. During this operation brush 627 of the distributor SD¹ engages the ring 630 and segment 633 to connect ground through wipers 618 and 634 to the winding of relay 516, whereupon this relay energizes and remains operated as long as brush 627 is in engagement with the segment 633. The energization of relay 516 opens the locking circuit for relay 517 which thereupon restores to open the original energizing circuit for relay 519. The latter relay, however, remains energized over the locking circuit described therefor. The energization of relay 516 also establishes a circuit extending from grounded battery through the alternate contact of relay 516, the inner right-hand contact of relay 519, winding of slow-to-release relay 518, and the left-hand normal contact of relay 521 to ground. Relay 518 energizes and locks through its inner left-hand contact and winding to ground at the left-hand normal contact of relay 521. The energization of relay 518 closes, at its right-hand alternate contact, an obvious locking circuit for relay 504.

As the brush 627 approaches the end of its revolution and disengages segment 633, relay 516 is released, together with relays 603 and 610, which were held energized by the same ground which caused the operation of relay 516. The release of relay 603 opens a holding circuit for relay 600 which thereupon restores to again connect start conductor 512 to the stepping magnets 604, 605 and 606.

When the code of impulses is received by the mechanism of Fig. 8 locking relays 800, 801, 803, 805 and 806 are operated to cause the energization of associated pyramid relays which select the conductor 849. An impulse of negative 120 volt polarity is then connected to the conductor 849 and extended to ground through the left-hand winding of the differential relay 721 to operate this relay, which thereupon locks through its right-hand winding. This impulse of current is also extended over the conductor 849 to ground through the left-hand winding of differential relay 729, which also operates but immediately releases upon the termination of the impulse inasmuch as no locking circuit is established for this relay, relay 726 being now in normal condition. The operation of relay 729, at this time, performs no function. Energization of relay 721 establishes a circuit extending from grounded battery through the windings of busy signal magnets 718, 719 and 720 in series, and the left-hand alternate contacts of relay 721 to ground. The busy signal magnets are operated to indicate before the various outward jacks at office Z the busy condition of the toll line L. The energization of relay 721 also establishes a circuit to light the lamp 730 before the "in" operator's position and individual to line L, said circuit extending from grounded battery through the lamp 730, the left-hand contact of relay 731, the outer left-hand contact of relay 704, the left-hand contact of relay 703, and the outer left-hand contact of relay 721 to ground.

"In" operator at office Z answers the incoming call on line L.

The "in" operator, observing the lighted condition of lamp 730, inserts the plug 700 of a cord circuit A' into the jack 732 and thereby establishes a circuit extending from grounded battery through the left-hand winding of relay 704, winding of relay 731, sleeve contacts of jack 732 and plug 700, and the winding of relay 702 to ground. Relays 702, 731 and 704 operate in this circuit, the opening of the left-hand contact of relay 731 and the outer left-hand contact of relay 704 breaking the circuit for lamp 730, which is thereupon extinguished. The operation of relay 704 also establishes an energizing circuit for slow-to-release relay 726 extending from grounded battery through the winding of relay 726, the normal contact of relay 729, the right-hand contact of relay 704, and from thence to ground through the left-hand contacts of relay 721, this ground also providing a locking circuit for relay 704. The operation of relay 726 at this time performs no function. The operation of relay 731 also establishes a circuit extending from grounded

battery through the right-hand winding of relay 705, the alternate contact of relay 731, the normal contact of relay 728, and from thence in series through the right-hand 5 normal contacts of relays 725 and 703 to ground. Relay 705 energizes but its operation at this time has no effect except to connect ground through its inner right-hand 10 contact to the windings of the busy signal magnets 718, 719 and 720, which have already been operated by the energization of relay 721.

The operator at office Z, upon actuating her listening key 741, connects her telephone 15 set to line L and thereby establishes a talking connection with the operator at office X who has previously operated her listening key 141. Upon ascertaining the number of the desired party from the operator at 20 office X, the operator at office Z then proceeds to complete the connection in a well-known manner through apparatus which forms no part of the present invention.

25 *Operator at office X signals the operator at office Z after the connection has been established.*

When the calling subscriber terminates 30 the call the operator at office X receives a disconnect signal in a manner well known in the art, and upon receiving this signal she transmits another signal to the office Z which is the same as the one transmitted when first establishing the connection. This 35 signal is sent by the operator at office X pressing the ringing key 140 in the cord circuit A in response to which the relay 106 is energized to again cause the operation of relay 107 which in turn operates 40 relay 108, the latter relay then locking as before described. Upon the release of the ringing key relays 106 and 107 release, and upon the closure of the normal contacts of the latter relay the start conductor 112 and 45 the individual conductor 113 are again grounded as previously described, it being recalled that the relay 105 is at this time energized and locked to ground at the outer left-hand contact of relay 110, which is 50 also locked under the control of the left-hand normal contact of relay 111. The grounding of conductors 112 and 113 initiates the operation of the mechanism of Fig. 2 to transmit the same code of impulses 55 to the mechanism of Fig. 4, which was transmitted when the call was first initiated.

The translating mechanism of Fig. 4, including the locking and pyramid relays, then 60 operate to again select the conductor 449 and apply thereto a negative impulse of 120 volt polarity which is extended to ground through the left-hand winding of relay 500. This impulse has no effect on this relay since the same is already operated and locked. 65 The impulse is further extended through the

outer left-hand alternate contact of relay 500, and from thence through the right-hand winding of relay 507 to ground. The relay 507 now operates and locks in a circuit traceable from ground through the left-hand winding of said relay, the right-hand contact thereof, and the contact of relay 508 to grounded battery, this latter relay, together with the relay 308, having been energized when connection was first established 70 and being held energized under the control of relay 519. In energizing, relay 507 opens, at its normal contact, the holding circuit for relays 308 and 508, and these relays, after an interval, restore, the release of relay 508 80 opening the locking circuit for relay 507, which thereupon releases. The operation and release of relay 308 perform no function while signals are being transmitted from office X to office Z but accomplish the same 85 results as just described in connection with relay 508 when signals are being transmitted from office Z to office X. While relay 507 is energized and locked under the control of relay 508, a circuit is established for slow-to-release 90 relay 522 extending from grounded battery through the winding of said relay, the left-hand alternate contact of relay 507, the normal contact of relay 503, and the outer right-hand contact of relay 519 to ground, the latter relay having previously 95 been energized under the control of relay 517 and locked under the control of relay 521. Relay 522 operates and in closing its alternate contact establishes an energizing circuit for relay 517 which again locks. Following the release of relay 507 relay 522 restores whereupon start conductor 512 and individual conductor 513 are grounded under the control of alternate contacts of relay 100 517 and normal contacts of relay 522. The grounding of the conductors 512 and 513 again initiates the operation of the sending mechanism of Fig. 6 to transmit to the receiving mechanism of Fig. 8 the same code 105 of impulses that was transmitted from office X to office Y. This code of impulses, upon being received at office Z, is translated to select the conductor 849 and apply thereto an impulse of negative 120 volt polarity, 110 which now causes the operation of relay 729, which then locks through its right-hand winding and contact to ground at the contact of relay 726. The opening of the normal contact of relay 729 opens the holding 115 circuit for relay 726, which then restores. This relay being slow to release, the locking circuit for relay 729 will be maintained an appreciable interval. During this interval 120 a circuit is established for the slow-to-release relay 733 extending from grounded battery through the winding of relay 733, the left-hand alternate contact of relay 729, the right-hand contact of relay 704, which is now operated and locked, and from thence 125 130

to ground through the left-hand contacts of relay 721, which is also operated and locked. Relay 733 energizes in this circuit and thereby connects ringing current to the line 5 L over a circuit extending from a source of ringing current through the lower alternate contact of relay 733, the ring contacts of jack 732 and plug 700, condenser 734, the right-hand winding of the ringing response relay 735, tip contacts of plug 700 and jack 732, and the upper alternate contact of relay 733 to ground. Relay 735 responds to the ringing current thus applied to the line and locks through its left-hand winding and contact to ground at the contact of relay 702. Following the locking of relay 735, relay 733 releases to disconnect ringing current from the line. The closure of the contact of relay 735 establishes an obvious circuit 10 for lighting the supervisory lamp 736. The operator at office Z responds to the lighting of this lamp by throwing her listening key 741 which places her in communication with the operator at office X.

15 The operators may now converse and on being informed by the operator at office X that the call has been terminated by the calling subscriber, the operator at office Z removes the plug 700 from the jack 732. This act causes the release of relays 702, 731 20 and 735 and the extinguishment of the lamp 736. The release of relay 731 opens the previously described circuit for relay 705 which operated but performed no function at the time that the "in" operator originally responded to the call.

25 After giving the disconnect signal the operator at office X removes the plug 100 from the jack 101, whereupon relays 102 and 103 release. Relay 104, which originally operated in series with relay 103, remains energized in the locking circuit described therefor. A condition now exists wherein relays 104, 105, 110 and 126 are operated. Due to the deenergization of relay 103 a circuit is 30 now established for the release control relay 111 extending from grounded battery through the left-hand contact of relay 109, the winding of relay 111, the right-hand contact of relay 110, the right-hand normal contacts of relays 137 and 131 in series, the normal contact of relay 128, and the right-hand normal contacts of relays 125 and 103 in series to ground. Relay 111 energizes and locks to ground through its inner left-hand contact. In operating, relay 111 disconnects ground from its left-hand normal contact to open the locking circuit for relay 110, which, after an interval, releases and thereby 35 breaks, at its outer left-hand contact, the original locking circuit for relay 105. Before this contact is opened, however, the outer left-hand alternate contact of relay 111 is closed to maintain the locking circuit for relay 105. The closure of the outer right-hand alternate contact of relay 111 grounds the start conductor 112 through the inner right-hand contact of relay 107. The closure of the inner right-hand alternate contact of relay 111 establishes a 40 circuit extending from ground through the winding of relay 258, the mentioned contact of relay 111, the outer right-hand contact of relay 107, the outer right-hand contact of relay 105, and the individual conductor 113 which is connected to a terminal individual to line L over which wiper 207 of switch D passes. The grounding of the start conductor 112 again causes stepping magnets 204, 205, and 206 to operate and step 45 the wipers of switches B, C and D over their associated rows of terminals. When wiper 207 engages the terminal to which conductor 113 is connected, relays 203 and 258 operate in series, and the energization of relay 203 causes the wipers of switches B, C and D to come to rest upon the terminals individual to the line L, as before described. The relay 258 also operates to establish an obvious energizing circuit for relay 243, which, 50 in closing its right-hand alternate contact, connects negative potential to segment 242 of the sending distributor SD. The energization of relay 203 again establishes the 55 energizing circuit for relay 200 which, in operating, disconnects the start conductor 112 from the stepping magnets of the switches B, C and D. The operation of relay 203 also initiates the operation of switch E, as 60 before described, and the wipers of this switch thereupon come to rest upon the desired terminals when the wiper 212 engages the terminal to which ground is connected through the relay 258, conductor 113, wiper 207, and the right-hand contact of relay 203. This ground operates the relay 210 to permanently open the circuit of the stepping magnet 211 and to close the circuit for operating the start magnet 228 of the sending distributor. A code of impulses is now 65 transmitted from office X to the receiving mechanism of Fig. 4 at office Y, and this code is the same as that originally transmitted when the call was initiated with the exception of the eighth and last impulse controlled by the relay 243, said impulse being now negative instead of positive. As this series of impulses is received by the receiving distributor RD, locking relays 400, 401, 403, 405, 406 and 407 are operated, the operation 70 of the latter relay being due to the closure of the upper contact of polar relay 450 in response to the eighth impulse of negative polarity, this impulse being received when the brush 434 engages the segment 446. The pyramid relays now respond, as before described, to select the conductor 449, whereupon an impulse of 120 volt current is connected to this conductor. Inasmuch as relay 407 is now operated this impulse will be 75

of positive instead of negative polarity. The result of the application of this positive impulse of 120 volt current will presently be described.

- 5 As the brush 227 of the sending distributor is revolving, relays 203 and 210 are maintained energized as before by the ground connected to the ring 230 and segment 233, and this ground also operates relay 109. Relays 203, 210 and 109 remain energized until the segment 233 is disengaged by brush 227 at the termination of its revolution, whereupon these relays release. When relay 109 energizes, the locking circuit for relay 111 is opened and this relay restores. The removal of ground from the outer left-hand alternate contact of relay 111, opens the locking circuit for relay 105 which then releases. Restoration of relay 111 also causes the release of relay 258. The release of relay 105 is followed by the release of relays 104 and 126 which were held operated by the ground at the inner right-hand contact of relay 105. This ground also maintained the busy signal magnets 118, 119 and 120 operated and these magnets therefore release upon the deenergization of relay 105 to indicate the idle condition of the toll line L. The apparatus of Fig. 1 is now in its normal condition.

While the brush 227 is in engagement with segment 233 an obvious locking circuit for relay 243 is maintained, but after the eighth impulse of the series has been transmitted and the brush 227 has disengaged segment 233, the locking circuit for relay 243 is opened and this relay thereupon releases. Relays 200, 203 and 210 also release as soon as the brush 227 disengages the segment 233. Therefore, as soon as the brush 227 completes its revolution the apparatus of Fig. 2 is in its normal condition. The receiving mechanism of Fig. 4 is restored to normal in the same manner as previously described.

The positive impulse of 120 volt current which is connected to the conductor 449 causes the release of differential relay 500, whereupon a circuit is established for the release control relay 521 extending from grounded battery through the left-hand normal contact of relay 516, winding of relay 521, the outer left-hand contact of relay 518, which is now energized and locked, the left-hand normal contacts of relays 502, 501 and 500 in series, and the outer normal contact of relay 509 to ground. Relay 521 energizes and locks through its winding and inner left-hand alternate contact, and, in opening its left-hand normal contact, breaks the locking circuit for relay 518, which relay, after an interval, restores. The opening of the right-hand alternate contact of relay 518 interrupts the original locking circuit for relay 504, but before re-

lay 518 can release a substitute locking circuit is provided for relay 504 by the connection of ground to the outer left-hand alternate contact of relay 521. Relay 504 therefore remains operated. The energization of relay 521 also opens, at its left-hand normal contact, the locking circuit for relay 519 which relay thereupon restores. The removal of ground from the outer right-hand contact of relay 519 breaks the holding circuits for relays 308 and 508, which were operated a second time when the relay 507 released following the opening of the locking circuit for relay 507 caused by the release of relay 508. The second operation of relays 308 and 508 performs no functions. In response to the opening of the holding circuit for relays 308 and 508, these relays restore to normal. Relays 504 and 521 are now the only relays at the intermediate office which are operated. The closure of the outer right-hand alternate contact of relay 521 grounds the start conductor 512 through the outer normal contact of relay 522. When relay 521 energizes, the individual conductor 513 is also grounded through relay 658, the inner right-hand alternate contact of relay 521, the inner normal contact of relay 522, and the inner right-hand alternate contact of relay 504. The ground on the conductor 513 is extended to the terminal over which wiper 607 of switch D' passes. In the same manner as previously described in connection with the transmission of the last code of impulses from Fig. 2, the apparatus of Fig. 6 responds to the grounding of the conductor 512 to transmit this same code of impulses to the receiving mechanism at office Z. When wiper 607 of switch D' engages the terminal to which the conductor 513 is connected, relays 603 and 658 operate, the operation of the latter causing the energization of relay 643 to connect negative current to the segment 642 of the sending distributor SD¹. The receipt of the series of impulses by the receiving mechanism RD¹ results in the operation of the locking relays 800, 801, 803, 805, 806 and 807, the operation of the latter relay resulting from the connection of negative polarity to the segment 642 of the sending distributor SD¹. The pyramid relays controlled by the operated locking relays are now energized to again select the conductor 849, whereupon an impulse of positive 120 volt current is connected through the right-hand alternate contact of relay 807 to the conductor 849, and through the left-hand winding of differential relay 721 causing the release of the latter relay. This positive impulse has no effect upon the differential relay 729. At the termination of the impulse the mechanism of Fig. 8 is restored to normal in the manner previously described. The release of relay 721 disconnects ground

through its left-hand alternate contacts from the windings of the busy signal magnets 718, 719 and 720, whereupon these magnets release to indicate an idle condition of the line L before the outward jacks at office Z. The opening of the left-hand alternate contacts of relay 721 also breaks the locking circuit for relay 704 and the holding circuit for relay 726, these relays thereupon restoring to normal. The apparatus of Fig. 7 is now in its normal condition. When the brush 627 of the sending distributor SD¹ engages the segment 633, a holding circuit is provided for relays 603 and 610, a locking circuit is established for relay 643 and relay 516 is energized. The operation of the latter relay opens the locking circuit for relay 521 which, in restoring, disconnects ground from the locking winding of relay 504, whereupon this relay releases. The apparatus of Fig. 5 is then in its normal condition. The release of relay 521 causes the de-energization of relay 658 but relay 643 remains operated in its locking circuit. When brush 627 disengages the segment 633 the relays 600, 603, 610 and 643 restore in a manner which is now believed to be obvious, thus leaving the apparatus of Fig. 6 in its normal condition.

30 *Operator at office X signals the "out" operator at office Z.*

Let it be assumed for the purpose of describing this portion of the operation of the circuit that a call has been originated at office Z and extended to office X. In this event the operation of signaling the "in" operator at office X is exactly the same as that already described in connection with the extension of an original call from office X to office Z. In Fig. 7, which is a duplicate of Fig. 1, relays corresponding to relays in Fig. 1 and similarly numbered, except for the hundreds digits, operate in the same manner and produce the same results as were described in connection with the latter relays. As a result of the insertion of plug 700 of the cord circuit A' into the jack 701 and the consequent operation of the relays in Fig. 7, a sending mechanism indicated by the rectangle SD², and similar in all respects to that shown in Fig. 2, operates to transmit the code of impulses individual to the line L and to the "in" operator's position at office X to the receiving mechanism indicated at RD². The conductor 549 is thereby selected and the 120 volt impulse of current of negative polarity applied to said conductor operates the relay 300 individual to the "in" operator's position. From this point the operation is the same as that described in connection with Fig. 5, the relays in Fig. 3 involved in this operation being numbered the same as those in Fig. 5, with the exception of the hundreds dig-

its. The operation of the mechanism of Fig. 3, in response to the impression of a negative impulse upon the conductor 549, effects the grounding of the conductors 312 and 313, with the result that a sending mechanism represented by the rectangle SD³ and similar in all respects to the apparatus shown in Fig. 2, is operated to again transmit the code of impulses individual to the line L and to the "in" operator's position. This code is received by the mechanism indicated at RD³, similar to the receiving mechanism of Fig. 4, which then operates to select a conductor 149 in the same manner that conductor 849 was selected. Relay 121 is then energized in the same manner that relay 721 was operated. From the previous description of operation resulting in the energization of relay 721, it is believed that the effect of the operation of relay 121 will be readily understood, it being borne in mind that reference characters applied to like parts in Figs. 1 and 7 are the same with the exception of the hundreds digits.

The occasion for an operator at office X calling the "out" operator at office Z arises when the "in" operator at office X, on a call incoming to this office, fails for some reason to secure a connection to the wanted subscriber. In this event she informs the calling operator at office Z of her inability to complete the connection to the desired party and transfers the ticket or record of the call to the "out" or "delayed call" operator at office X. The originating or calling operator at office Z, upon being informed by the "in" operator at office X that connection to the wanted line cannot be obtained, also transfers the record of the call to the "out" or "delayed call" operator at her office. The "out" or "delayed call" operator at office X then endeavors from time to time to secure a connection to the wanted party, and when successful proceeds to call the "out" or "delayed call" operator at office Z who then signals the calling subscriber after which the call is completed in accordance with well-known practice.

To signal the "out" operator at office Z, the "out" operator at office X inserts plug 100 of a cord circuit A into a jack 124 and thereby establishes a circuit extending from ground through the winding of relay 102, sleeve contacts of plug 100 and jack 124, the winding of relay 125, and the left-hand winding of relay 104 to grounded battery. Relays 104 and 125 energize in series and the operation of the latter establishes a circuit for relay 116 extending from grounded battery through the right-hand winding of said relay, the alternate contact of relay 125, and the right-hand normal contact of relay 103 to ground. The operation of relay 116 closes a locking circuit for relay 104 by connecting ground to the inner right-

hand contact of relay 116 and the right-hand contact and winding of relay 104. The operation of relay 116 also closes, at its inner right-hand contact, an obvious circuit for 5 operating busy signal magnets 118, 119 and 120 to indicate the busy condition of the line L.

The operator now depresses her ringing key 140 to energize relay 106 as previously 10 described, whereupon relay 107 operates to establish the energizing circuit for relay 108, which thereupon locks. Relay 110 is also operated and locked as before. When the operator releases the ringing key, relay 106 15 restores to open the circuit for relay 107 which, after an interval, releases. When relay 107 closes its normal contacts the start conductor 112 and the conductor 114, individual to the toll line L, are grounded, 20 the circuit for conductor 112 being the same as previously described, while the path for grounding the conductor 114 extends from ground through the outer right-hand contact of relay 108, the right-hand normal contact 25 of relay 111, the outer normal contact of relay 107, the outer right-hand alternate contact of relay 116 to the conductor 114. The grounding of start conductor 112 causes the operation of stepping magnets 204, 205 and 206, as previously described, whereupon the 30 wipers of switches B, C and D are stepped until ground is encountered upon one of the terminals over which wipers 207, 208 and 209 pass. In the present instance this ground 35 is found upon a terminal over which wiper 208 passes and to which conductor 114 is connected. Engagement with this terminal by wiper 208 closes a circuit for relay 202 extending from grounded battery through 40 the right-hand winding of said relay and the wiper 208 to ground on the conductor 114. Relay 202 energizes to stop the operation of stepping magnet 205 and on energizing closes the circuit for operating relay 200. 45 The energization of the latter relay disconnects the start conductor 112 from stepping magnets 204 and 206. The wipers of switches B, C and D therefore come to rest upon their respective terminals which are 50 individual to the line L. The energization of relay 202 connects ground from its left-hand alternate contact to the common conductor extending to the contact and winding of the stepping magnet 211 through the normal contact of relay 210. The energization 55 of relay 202 also extends the ground connected to wiper 208 through the right-hand contact of relay 202 to certain terminals associated with wiper 212 of switch E. The 60 closure of the circuit for stepping magnet 211 operates this magnet to step the wipers of switch E from the terminals then engaged thereby until wiper 212 engages the first terminal in its bank to which ground 65 is connected. Again assuming that the

wipers of switch E are on the third terminals of their respective banks, it will be seen that said wipers will be caused to take two steps to the fifth terminals thereof, at which time the wiper 212 encounters the ground through the right-hand contact of relay 202, which ground is then extended through the left-hand winding of relay 210 to grounded battery. Relay 210 then operates to stop the operation of the stepping magnet 211 and the wipers of switch E thereupon come to rest upon the fifth terminals in their respective banks. 70

The apparatus is now in condition to transmit the code of impulses individual to the toll line L and to the "out" operator's position at office Z. This particular code of impulses is determined by the position of the wipers 219 to 225 inclusive of switch E and the wipers 245 to 249 of switch C. 75 With the mentioned wipers of switches E and C on the fifth terminals appearing on the drawing, it will be seen that the polarities of the first seven impulses of the present code are positive, negative, positive, negative, positive, negative and negative, transmitted in the order named. The eighth impulse is again determined by the condition of the relay 243, which, in this operation, is normal as before described, thereby causing a positive impulse to be transmitted. By reference to the previous description it is believed that the operation of transmitting this code of impulses will be readily understood. 80 As the impulses of the code are received by the receiving distributor RD, relays 401, 403, 405 and 406 are operated and locked under the control of relay 408. The energization of the above-mentioned locking relays causes the energization of the pyramid relays 409, 412 to 415, and 420 to 426 in the manner now believed to be obvious. 85 With these pyramid relays operated, when the brush 434 of the receiving distributor RD engages segments 447 and 448, a negative 120 volt impulse of current is transmitted from the source through the normal contact of relay 407, segment 447, brush 434, segment 448, the right-hand alternate contact of relay 406, the right-hand alternate contact of relay 409, the left-hand normal contact of relay 411, the left-hand alternate contact of relay 414, the right-hand normal contact of relay 418, the right-hand alternate contact of relay 425, the left-hand normal contact of relay 430, conductor 451, and from thence through the left-hand winding of the differential relay 501 to ground. 90 This impulse of current causes relay 501 to energize and then lock through its right-hand winding and inner right-hand contact. The effect of the operation of relay 501 will presently be described. After the impulse of current has been transmitted brush 434 disengages the segment 440 and thereby 95

causes the release of relay 408 which, in turn, effects the release of the locking and pyramid relays, which have been energized, thus restoring the receiving mechanism to 5 normal. While the code of impulses was being transmitted a ground was connected through the ring 230 and segment 233, and from thence in multiple through the right-hand winding of relay 210, the wiper 218, 10 the right-hand winding of relay 202, the wiper 251 of switch C, and the winding of relay 109 to grounded battery. This ground maintains relays 210 and 202 energized and causes the operation of relay 109. The energization of the latter relay opens the locking circuit for relay 108 which then de-energizes to disconnect ground from the conductors 112 and 114. Relays 104, 110, 116 and 125 remain energized, relay 110 20 providing, at its outer left-hand contact, a locking ground for relay 116.

When relay 501 energizes and before the impulse of current is disconnected from conductor 451, this impulse is transmitted 25 through the outer right-hand contact of relay 501 to ground through the right-hand winding of the relay 507. Relay 507 operates but does not lock inasmuch as relay 508 is not, at this time, energized. Therefore, 30 relay 507 will release at the termination of the impulse without performing any function. The operation of relay 501 also establishes a circuit for relay 505 extending from grounded battery through the right-hand 35 winding of relay 505, the left-hand alternate contact of relay 501, the left-hand normal contact of relay 500, and the outer normal contact of relay 509 to ground. When relay 505 energizes in this circuit an operating 40 circuit for relay 517 is established, said circuit being traceable from grounded battery through the right-hand contact of relay 516, winding of relay 517, the normal contact of relay 518, the outer right-hand contact of relay 505, and the outer normal 45 contact of relay 509 to ground. Relay 517, in operating, locks through its winding and inner left-hand contact, and at its inner right-hand contact connecting ground, by 50 way of the outer normal contact of relay 522 to the start conductor 512. The closure of the outer right-hand contact of relay 517 connects ground through the right-hand normal contact of relay 521, the inner normal 55 contact of relay 522, and the inner right-hand contact of relay 505 to the individual conductor 514. When relay 517 operates, the previously described circuit for relay 519 is established and this relay locks to ground 60 at the left-hand normal contact of relay 521. Relay 505, in closing its outer left-hand contact, establishes an obvious energizing circuit for the busy signal magnets 320 and 520, which thereupon operate to indicate the busy 65 condition of the line L at the office Y.

The grounding of the conductors 512 and 514 has the same effect upon the mechanism of Fig. 6 that the grounding of the conductors 112 and 114 had upon the mechanism of Fig. 2. The code of impulses individual to the toll line L and to the "out" operator's position at office Z is now transmitted by the sending distributor SD¹ to the receiving distributor RD¹. When the relay 602 energizes in response to the engagement of wiper 608 with the terminal to which ground is connected over the conductor 514, relay 600 operates to disconnect the start conductor 512 from the windings 70 of the various stepping magnets 604, 605 and 606. While brush 627 of the sending distributor SD¹ is revolving, relays 602 and 610 are held operated and relay 516 is energized. The closure of the left-hand alternate contact of relay 516 establishes the previously described energizing circuit for the slow-to-release relay 518, which thereupon energizes and locks as before. When brush 627 disengages the segment 633, the relays 602, 610 and 516 release and the release of relay 602 causes the restoration of relay 600. 75 80 85 90 95 100 105 110 115 120 125

In response to the series of impulses transmitted to the receiving mechanism of Fig. 8, the locking relays 801, 803, 805 and 806 and the pyramid relays associated therewith are energized to select the conductor 851. An impulse of negative 120 volt current is now applied to the conductor 851 after which the mechanism of Fig. 8 restores to normal in a manner now believed to be obvious. The application of this impulse of current to the conductor 851 causes the energization of the differential relay 722, which relay then locks. When this relay energizes, this impulse of current is transmitted through the outer right-hand contact of relay 722 to the left-hand winding of relay 729, which also responds to the impulse but does not lock inasmuch as the relay 726 is not, at this time, operated. The operation of relay 729 and its subsequent release at the termination of the impulse have no effect upon the circuit at this time. Upon the closure of the outer left-hand contact of relay 722, a circuit is established for lighting the line lamp 738 before the "out" operator's position, said circuit extending from grounded battery through the lamp 738, the left-hand contact of relay 737, the inner left-hand contact of relay 704, the left-hand contact of relay 725, and the outer left-hand contact of relay 722 to ground. The "out" operator, upon observing the lighted condition of lamp 738, inserts the plug 700 of a cord circuit, such as A', into the jack 739, whereupon a circuit is established extending from ground through the winding of relay 702, the sleeve contacts of plug 700 and jack 739, the winding of relay 737, and the left-hand winding of relay 704 130

to grounded battery. Relays 704 and 737 operate, the energization of the latter opening the circuit for the lamp 738, which is thereupon extinguished. Relay 704, upon energizing, locks through its right-hand winding and contact to ground through the left-hand contacts of relay 722. The closure of the alternate contact of relay 704 also effects the energization of relay 726 over an obvious circuit. The operation of relay 726 at this time has no effect.

The "out" operator at office Z upon actuating her listening key, establishes communication with the "out" operator at office X and upon being informed that the called party has been reached, the "out" operator at office Z then proceeds to secure a connection to the calling subscriber after which the two subscribers are connected over the line L in a well-known manner. When relay 737 energizes, a circuit is established for relay 716 extending from grounded battery through the right-hand winding of relay 716, the alternate contact of relay 737, the right-hand normal contact of relay 731, the normal contact of relay 728, and the right-hand normal contacts of relays 725 and 703 in series to ground. Relay 716 energizes but its operation at this time has no effect upon the circuit, except to connect, at its inner right-hand contact, an additional holding ground to the windings of the busy signal magnets 718, 719 and 720.

35 "Out" operator at office X signals "out" operator at office Z after the connection has been established.

When the calling subscriber terminates the call the "out" operator at office X receives the usual disconnect signal, whereupon she depresses her ringing key in the cord circuit A to operate the ringing response relay 106, which causes the energization of relay 107 followed by the operation of relay 108, which relay is locked as before described. When the ringing key is released relay 106 restores and after an interval relay 107 closes its normal contacts. Relay 110 is already energized and locked by the previous operation of relay 108 so that when the normal contacts of relay 107 are closed upon the release of this relay, the start conductor 112 and the individual conductor 114 are grounded as before described. 55 The grounding of these two conductors initiates the operation of the mechanism in Fig. 2, which thereupon actuates to transmit the code of impulses individual to the line L and to the "out" operator's position in office Z. During the transmission of this code of impulses relay 109 is again operated to open the locking circuit of relay 108, which thereupon restores. The translating mechanism of Fig. 4 responds to the code of impulses received by the receiving distribu-

tor RD and again selects the conductor 451. The impulse of current then transmitted over this conductor has no effect upon the relay 501, which is already operated, and due to this fact the impulse is extended 70 through the outer right-hand contact of relay 501, and the right-hand winding of relay 507 to ground. Relay 507 operates and locks through its left-hand winding and right-hand contact to grounded battery at 75 the contact of relay 508, which is at this time operated due to the energized condition of relay 519. The opening of the normal contact of relay 507 breaks the circuit for relay 508, which relay, after an interval, 80 restores to open the locking circuit for relay 507. Before this latter relay releases, the circuit through the left-hand contact thereof, the normal contact of relay 503, and the outer right-hand contact of relay 519 is 85 closed to energize the relay 522. The operation of relay 522 again energizes relay 517, which locks as before. When relay 522 releases, following the deenergization of relay 507, the start conductor 512 and individual conductor 514 are grounded through contacts of relay 517 to start the operation of the sending mechanism of Fig. 6 to transmit the code of impulse individual to the line L 90 and to the "out" operator's position at office Z. When relay 507 releases, the circuit for energizing relays 308 and 508 is again established since relay 519 remains operated. The operation of relays 308 and 508, at this time, has no effect. While the code of impulses is being transmitted from office Y to the mechanism of Fig. 8 at office Z, relay 516 is operated to open the locking circuit for relay 517, which then restores. After the series of impulses has been 105 transmitted, relay 516 is released, together with the relays of the mechanism of Fig. 6, which have operated. The receiving mechanism of Fig. 8 responds to the code of impulses, in the same manner as previously set forth, to select the conductor 851 and to apply a negative impulse of 120 volt current thereto, which has no effect upon the relay 722 since this relay is now energized, but which extends through the outer right-hand contact of relay 722 and the left-hand winding of relay 729 to ground. The latter relay energizes and now locks, through its right-hand winding and contact, to ground at the contact of relay 726, which was energized when relay 704 operated in response to the insertion of plug 700 into jack 732. The opening of the normal contacts of relay 729 breaks the holding circuit for relay 726, 115 which, after an interval, restores to open the locking circuit for relay 729, following which this relay releases. However, before relay 729 restores a circuit is established for the ringing relay 733 extending from grounded battery through the winding of 120

this relay, the left-hand alternate contact of relay 729, the right-hand contact of relay 704, and the left-hand contacts of relay 722 to ground. Relay 733 operates to connect 5 ringing current over the line L and through contacts of the jack 732 and plug 700 to the right-hand winding of the relay 735 in the cord circuit A'. Relay 735 responds to the application of ringing current and causes 10 the lighting of the supervisory lamp 736, in the manner previously described, to signal the "out" operator, who then responds to the signal by operating her listening key. Upon being informed by the "out" operator at 15 office X that the call has been terminated, the operator at office Z removes plug 700 from jack 732, thereby releasing the apparatus associated with the cord A and also the relay 731. 20 After giving the disconnect signal, the operator at office X removes plug 100 from the jack 124, thereby causing the release of relays 102 and 125. The previously described circuit for the release control relay 111 through contacts of relays 109, 110, 137, 131, 128, 125 and 103 is thereupon established and relay 111 energizes and locks to ground the start conductors 112 and 114, the latter conductor being grounded through 25 the winding of relay 258. The closure of the outer left-hand contact of relay 111 provides another locking circuit for relay 116 before the original locking circuit for this relay is opened by the release of relay 110, 30 which release occurs after the left-hand normal contact of relay 111 is opened.

The stepping magnets 204, 205 and 206 respond to the grounding of the conductor 112 to step the wipers of switches B, C and 35 D until the wiper 208 of switch C engages the terminal to which grounded conductor 114 is connected, whereupon the switches are brought to rest in a manner now believed to be obvious. Relays 202 and 258 40 then operate in series through the wiper 208, the operation of the latter relay having the same effect as previously described. A code of impulses is now transmitted to the receiving mechanism at office Y, said 45 code being the same as that previously transmitted for the "out" operator's position at office Z, with the exception that the eighth impulse is of negative instead of positive polarity due to the operation of relay 243 under the control of relay 258. During the transmission of this code, relay 50 50 109 is operated to open the locking circuit for relay 111, which then restores. The opening of the right-hand alternate contacts of this relay disconnects ground from the conductors 112 and 114 and causes the release of relay 258, relay 243, however, remaining operated in the locking circuit established therefor through the segment 55 233 of the sending distributor SD. The re-

lease of relay 111 also disconnects ground from the locking winding of relay 116, which thereupon releases and in so doing disconnects ground, at its inner right-hand contact, from the windings of the busy signal magnets 118, 119 and 120. These magnets then release to indicate the idle condition of line L at office X. Following the release of relay 109 when brush 227 disengages the segment 233, the apparatus of 70 Figs. 1 and 2 will be restored to its normal condition in a manner which is now believed to be well understood.

The mechanism associated with the receiving distributor RD operates to translate the code of impulses received thereby to select the conductor 451 and to apply an impulse of positive 120 volt current to said conductor, the impulse being of positive polarity in this instance due to the fact that locking relay 407 is operated. This impulse is extended through the left-hand winding of relay 501 and causes the release of this relay. The release of relay 501 opens the original energizing circuit for relay 505 but this latter relay remains energized through its left-hand locking winding which is connected to ground at the right-hand alternate contact of relay 518, which is also locked at this time. The restoration of relay 501 also establishes the previously described energizing circuit for the release control relay 521 extending through contacts of relays 516, 518, 502, 501, 500 and 509. The relay 521, in operating, opens the locking circuit for relay 518 but before this relay can restore a substitute locking circuit for relay 505 is provided at the outer left-hand contact of relay 521. The removal of ground from the left-hand normal contact of relay 521 also opens the locking circuit for relay 519, which thereupon releases and in so doing disconnects, at its outer right-hand contact, the holding ground for relays 308 and 508, whereupon these relays restore to normal. In closing its right-hand alternate contacts relay 521 grounds the conductors 512 and 514, the latter conductor being grounded through the winding of relay 658, the inner normal contact of relay 522, and the inner right-hand alternate contact of relay 505. The grounding of the conductor 512 causes the operation of the stepping magnets 604, 605 and 606, and these magnets operate to step the wipers of switches B', C' and D' until the wiper 608 engages the terminal to which conductor 514 is connected, whereupon the wipers of the various switches are brought to rest. The same code of impulses, which was last described as having been transmitted from office X to office Y, is now sent to the receiving mechanism of Fig. 8 where it is received and translated with the result that conduc-

tor 851 is selected and a positive impulse of 120 volt current applied thereto. During the transmission of the impulses relay 516 is operated to open the locking circuit for relay 521 and this relay then releases to cause the restoration of relay 505. The apparatus of Fig. 5 is now in its normal condition with the exception of the relay 516, which is released when the brush 627 disengages the segment 633, this action also restoring the relays of Fig. 6 which have been operated.

The impulse of current of positive polarity which is transmitted over conductor 851 by the operation of the receiving mechanism of Fig. 8 causes the release of relay 722. The removal of ground from the left-hand contacts of this relay opens the locking circuit for relay 704, which relay, in releasing, causes the restoration to normal of relay 726, which latter relay reoperated after relay 729 was energized and released when the operator at office Z was signaled by the operator at office X. The release of relay 722 also opens the holding circuit for the busy signal magnets 718, 719 and 720, and these magnets then restore to indicate the idle condition of the line L at office Z. All the apparatus is now in its normal condition.

By reference to the previous description in which like parts are designated by the same reference characters with the exception of the hundreds digits throughout the drawings, it is believed that the operation of establishing calls from office Z to office X through the "in" and "out" jacks and the transmission of disconnect signals to office X will be readily understood.

Operator at office X initiates a call to the intermediate or through office Y.

When it is desired to establish a connection to a called subscriber through the intermediate or through office Y, the originating operator at the office X inserts the plug 100 of a cord circuit A into the "through" jack 127, thereby establishing a circuit extending from ground through the winding of relay 102, the sleeve contacts of plug 100 and jack 127, the winding of relay 128, and the left-hand winding of relay 104 to grounded battery. Relays 104 and 128 energize in series and the energization of relay 128 establishes an operating circuit for relay 117 extending from grounded battery through the right-hand winding of relay 117, the alternate contact of relay 128, and the right-hand normal contacts of relays 125 and 103 to ground. Relay 117, through its inner right-hand contact, establishes an obvious locking circuit for relay 104. When the inner right-hand contact of relay 117 and the right-hand contact of relay 104 are closed, a circuit is again established for the slow-to-re-

lease relay 126 which operates but has no effect upon the circuit at this time.

The operator now depresses her ringing key 140 to cause the successive energization of relays 106, 107, 108 and 110 as previously described. When the relays 106 and 107 release at the termination of the application of ringing current, the start conductor 112 is grounded through contacts of relays 107 and 108, as previously described, to again close the operating circuits for the stepping magnets 204, 205 and 206. Since the relay 117 is energized the individual conductor 115 is the one that is grounded when relay 108 operates, the circuit extending from ground through the outer right-hand contact of relay 108, the right-hand normal contact of relay 111, the outer right-hand contact of relay 107, and the outer right-hand alternate contact of relay 117 to the conductor 115. This ground is extended over said conductor to a terminal individual to the line L, over which the wiper 209 of switch B passes. The switches B, C and D now operate, as previously described, until the wiper 209 engages the terminal grounded by the conductor 115, whereupon the relay 201 energizes through its left-hand winding to open the operating circuit for the stepping magnet 204 and to cause the energization of relay 200, the latter operation breaking the continuity of the starting conductor 112 with the result that the other stepping magnets, 205 and 206, cease to operate. The wipers of switches B, C and D thereupon come to rest upon the respective terminals in their associated rows individual to the toll line L. The energization of relay 201 also grounds, at its left-hand alternate contact, the common conductor extending to the normal contact of relay 210, and the contact and winding of the stepping magnet 211 of the switch E. This stepping magnet then operates the wipers of switch E until wiper 212 engages a grounded terminal. With the wipers of the switch E in the position shown, the wiper 212 is now in engagement with a terminal which is grounded through the conductor 115, wiper 209, and the right-hand contact of relay 201, so that relay 210 will operate immediately to open the stepping circuit for magnet 211, whereupon the wipers of switch E remain in engagement with the third terminals in their associated rows.

The energization of relay 210 closes the previously described energizing circuit for start magnet 228 of the sending distributor SD, whereupon the brush 227 thereof is released to make a complete revolution, as previously described, whereby the code of impulses individual to the toll line L and to the "through" operator's position is transmitted over the path P to the receiving distributor RD. The polarities of the

first seven impulses of this code are determined by the positions of wipers 252 to 256 inclusive of switch B, and the wipers 219 to 225 inclusive of switch E. These impulses, named in the order of their transmission, are of positive, positive, positive, negative, positive, positive and then positive polarities. The eighth impulse of the code is again determined by the condition of relay 243 associated with the sending distributor, which, as before, is deenergized at this time so that the eighth impulse will be of positive polarity. The fourth impulse being the only one of negative polarity, it will be obvious from an understanding of the previous operation of the receiving distributor RD that only the locking relay 403 will be energized and locked. The energization of this relay causes the operation of the pyramid relays 412 to 415. It will thus be seen that when the brush 434 of receiving distributor engages the segments 447 and 448, an impulse of 120 volt negative polarity will be transmitted from the source through the normal contact of relay 407, the segment 447, brush 434, segment 448, the normal contact of relay 406, the left-hand normal contacts of relays 409 and 410, the left-hand alternate contact of relay 412, and the right-hand normal contacts of relays 416 and 421 to the conductor 452, and from thence in multiple to ground through the left-hand windings of the differential relays 303 and 502. The operation of these relays in this circuit will presently be described.

During the rotation of the brush 227 of the sending distributor SD, the relays 210 and 201 will be maintained operated, and relay 109 energized in a manner which is believed to be obvious from the previous description, relay 109 being now operated through the wiper 257 of switch B. The operation of relay 109 has the same effect as previously described. When the brush 227 passes from engagement with the segment 233, relays 109, 210 and 201 release and the deenergization of the latter relay opens the holding circuit for relay 200, which then restores.

The operation of relay 303 in response to the impulse of current received over conductor 452 has no effect at this time and this relay remains energized only for the duration of the impulse since relay 308 is not operated to establish a locking circuit for relay 303.

When the relay 502 operates it locks through its right-hand winding and inner right-hand contact, and at its left-hand alternate contacts closes an operating circuit for relay 506 extending from grounded battery through the right-hand winding of relay 506, the left-hand alternate contacts and armature of relay 502, the left-hand normal contacts of relays 501 and 500, in series,

and the outer normal contact of relay 509 to ground. The effect of the operation of relay 506 will presently be described. The closure of the outer left-hand alternate contact of relay 502 establishes a circuit to 70 light the lamp 310, extending from grounded battery through the lamp 310, the inner normal contact of relay 309, the outer left-hand alternate contact of relay 502, and from thence to ground over the energizing 75 circuit to inform the "through" operator that a call from office X is awaiting attention.

The closure of the outer left-hand contact of relay 506 establishes an obvious operating circuit for the busy signal magnets 320 and 520, which energize to indicate the busy condition of line L at office Y.

The energization of relay 506 also causes relay 517 to operate over a circuit traceable from grounded battery through the right-hand contact of relay 516, winding of relay 517, right-hand normal contact of relay 518, the outer right-hand contact of relay 506, and the outer normal contact of 85 relay 509 to ground. Upon the closure of the outer left-hand contact of relay 517, relay 519 operates and locks, as before described, to close the energizing circuits for 90 relays 308 and 508. The latter relays operate but at this time perform no function. The operation of relay 517 also grounds the conductors 512 and 515 in a manner which is now believed to be obvious, whereupon 95 the mechanism of Fig. 6 actuates to transmit to the mechanism of Fig. 8 at office Z the code of impulses individual to the line L and to the "through" operator's position at office Y. The receiving mechanism of Fig. 8 responds to this code of impulses and 100 selects the conductor 852, whereupon a 120 volt impulse of negative polarity is transmitted over said conductor to operate the relay 723. Relay 723 locks and in closing 105 its left-hand contact establishes an obvious circuit for operating the busy signal magnets 718, 719 and 720, which energize to indicate at office Z the busy condition of the line L. While the above-mentioned code of 110 impulses was being transmitted, relay 516 energizes in the same manner as previously described to establish the energizing circuit for relay 518, which thereupon locks. In energizing relay 516 causes the release of 115 relay 517. At the termination of the revolution of the brushes of the distributors SD¹ and RD¹, the mechanisms of Figs. 6 and 8 are restored to normal in a manner which is thought to be well understood. Relays 502, 506, 518 and 519 are energized and 120 locked and relays 308 and 508 are held operated by the ground at the outer right-hand contact of relay 519.

The "through" operator at office Y, upon observing the lighted condition of lamp 310, 125 130

inserts plug 323 of a cord circuit F into jack 324 and thereby establishes a circuit extending from ground through the sleeve relay 325, the sleeve contacts of plug 323 and jack 324, and the winding of relay 309 to grounded battery. Relays 309 and 325 operate, the former opening, at its inner normal contact, the circuit for lamp 310, which is then extinguished. The closure of 10 the outer alternate contact of relay 309 extends ground to the right-hand winding of relay 306 which thereupon operates but the energization of this relay at this time has no effect upon the circuit. The closure of 15 the inner alternate contact of relay 309 establishes a circuit for relay 531, said circuit being traceable from grounded battery through the winding of relay 531, the inner alternate contact of relay 309, the outer left- 20 hand contact and armature of relay 502, the left-hand normal contacts of relays 501 and 500, and the outer normal contact of relay 509 to ground. Relay 531 operates in this circuit to disconnect the office Y from office 25 Z over the line L while the connection is established between offices X and Y. The operator at office Y establishes communication with the calling operator at office X over the line L by actuating her listening 30 key 326, and upon ascertaining the number of the wanted subscriber proceeds to complete the connection in a well-known manner.

Operator at office X signals the operator at office Y after the establishment of a connection.

When the calling subscriber terminates the call by hanging his receiver upon its switchhook, the operator at office X receives 40 the usual supervisory signal and thereupon proceeds to signal the operator at office Y to inform her that the call has been terminated. This is done by actuating the ringing key 140 in the cord circuit A in response 45 to which relays 106, 107, 108 and 110 operate in the manner previously described. The conductors 112 and 115 are again grounded to cause the transmission from office X to office Y of the code of impulses individual 50 to line L and the "through" operator's position at office Y. The impulse of negative polarity which is transmitted over the conductor 452 as a result of the transmission of this code of impulses has no effect upon relay 502, which is already operated, but causes 55 the operation of relay 303, which thereupon locks through its right-hand winding and contact to grounded battery at the contact of relay 308, which is operated at this time. 60 The energization of relay 303 opens the holding circuit for relays 308 and 508 and these relays, after an interval, restore, the restoration of relay 308 breaking the locking circuit for relay 303 which also releases. Before relay 303 releases a circuit is estab-

lished extending from grounded battery through the winding of relay 327, the left-hand alternate contact of relay 303, and the outer right-hand alternate contact of relay 519 to ground. Relay 327 operates to connect 70 ringing current to the tip and ring conductors of line L so that, when current is extended through the tip and ring contacts of plug 323 and jack 324 and from thence through the left-hand winding of relay 328, 75 this relay responds to this impulse and locks through its right-hand winding and contact to ground at the contact of relay 325. The operation of relay 328 establishes an obvious circuit for lighting the supervisory lamp 329. 80 The ringing current which is applied to the line L by the operation of relay 327 is prevented from affecting the ringing response relay 106 at office X by the condensers and filters included in metallic telegraph mechanism generally indicated at M, which is commonly employed in toll switching systems. Only so much of the telegraph mechanism is shown as is necessary to an understanding of the manner in which the ringing 85 current is prevented from affecting apparatus at the distant office. Like mechanisms are shown at M¹ (Fig. 5) and indicated by rectangles M² and M³ at offices X and Z for preventing the passage of ringing current 90 over the line between adjacent offices. When relay 303 releases it causes the restoration of relay 327 and again establishes an energizing and holding circuit for relays 308 and 508. The operation of these relays has no effect 100 upon the circuit at this time. The operator at office Y throws a listening key in response to the lighting of the lamp 329 and thereby causes the release of relay 328 and the extinguishment of the lamp 329. Upon being 105 informed by the operator at office X that the call has been terminated the operator at office Y removes plug 323 from jack 324. Relays 309 and 325 thereupon release, the release of the former causing the restoration 110 of relay 306. The apparatus of Fig. 3 is then in its normal condition. The release of relay 309 also opens the holding circuit for relay 531 and this relay then restores to 115 connect office Y to office Z over the line L.

After instructing the operator at office Y to disconnect, the operator at office X removes plug 100 from jack 127, whereupon relays 102 and 128 release. The restoration of relay 128 establishes the previously described circuit for the release control relay 111 which, in opening the locking circuit for relay 110, causes the restoration of this relay but relay 117 remains operated through its locking winding to ground at the outer left-hand contact of relay 111. The continued operation of relay 117 maintains relays 104 and 126 operated.

The energization of relay 111 causes the grounding of the conductors 112 and 115, 130

whereupon the mechanism of Fig. 2 operates to transmit a code of impulses to office Y similar to the code which is individual to line L and the "through" operator's position, with the exception that the last impulse is of negative instead of positive polarity, this being due to the operation of relays 258 and 243, as previously described. The code of impulses being received by the mechanism of Fig. 4 causes the selection of the conductor 452 and the transmission thereover of a positive impulse. This positive impulse has no effect upon the relay 303 but causes the relay 502 to release. The effect of the restoration of relay 502 will be presently described.

While the code of impulses was being transmitted to office Y, relay 109 operated, as previously described, to open the locking circuit for relay 111, whereupon relays 117, 104 and 126 release in the order named. When brush 227 of the sending distributor SD completes its revolution, relay 109 releases and the apparatus of Figs. 2 and 4 is restored to normal in a manner now believed to be understood.

The release of relay 502 establishes the previously described energizing circuit for release control relay 521, which operates to initiate the transmission of a code of impulses to office Z similar to that transmitted to office Y. The receiving mechanism of Fig. 8 responds to this code of impulses and transmits an impulse of current having a positive potential to the conductor 852 which causes the release of differential relay 723 followed by the release of busy signal magnets 718, 719 and 720.

The operation of relay 521 opens the locking circuits for relays 518 and 519, the latter relay thereupon restoring to remove ground from the windings of relays 308 and 508, and these relays thereupon release. When relay 516 operates during the transmission of the code of impulses to office Z, relay 521 restores and opens the locking circuit for relay 506, which then releases. When relay 506 releases the circuit is opened for the busy signal magnets 320 and 520, and these magnets release to indicate the idle condition of line L at office Y. The apparatus is now in its normal condition.

Operator at office Y signals the operator at office X after the establishment of the connection.

If, while a connection is established between offices X and Y, the operator at office Y should desire to communicate with the operator at office X, she may do so by actuating her ringing key 340 in the cord circuit F and thereby cause the operation of the ringing response relay 330 which is now bridged across the line L due to the energization of relay 502. The operation of the

relay 330 connects ground through its contact to the winding of the slow-to-release relay 322, which responds to the closure of this circuit and thereby operates relay 317, which then locks. Relay 319 then operates over an obvious circuit and locks through its winding and left-hand contact to ground at the left-hand contact of relay 321. When relay 322 releases following the restoration of the ringing key in the cord circuit and consequent deenergization of relay 330, start conductor 312 is grounded through the inner right-hand contact of relay 317 and the outer normal contact of relay 320, while the individual conductor 315 is grounded through the outer right-hand contact of relay 317, right-hand normal contact of relay 321, inner normal contact of relay 322, and the inner right-hand contact of relay 306, which is operated at this time due to the energized condition of relay 309. The grounding of the two conductors 312 and 315 initiates the operation of the sending mechanism SD², which is similar in all respects to the sending mechanism shown in Figs. 2 and 6, and by reason of the grounding of the conductor 315 a code of impulses will be transmitted by the mechanism SD² to receiving mechanism RD², which code is individual to the line L and to the "out" operator's position and is similar to the code which was initially transmitted from office X to office Y when the call was initiated. This code of impulses, upon being received at office X, causes the selection of the conductor 152 and the transmission thereover of an impulse of negative polarity by the receiving mechanism at office X, this negative impulse being effective to operate relay 123, which thereupon locks. This impulse is also transmitted through the outer left-hand contact of relay 117, which is now operated, and the right-hand winding of relay 129 to ground. Relay 129 operates and locks through its left-hand winding and right-hand contact to ground at the contact of relay 126, which is also operated at this time due to the operation of relays 104 and 117. The operation of relay 129 opens the holding circuit for relay 126, whereupon this relay, after an interval, restores to open the locking circuit for relay 129 following which the latter relay releases. The release of relay 129 again establishes the energizing and holding circuit for relay 126. While the relay 129 is operated a circuit is established for slow-to-release relay 133 extending from grounded battery through the winding of said relay, the left-hand alternate contact of relay 129, the right-hand contact of relay 104, and the inner right-hand contact of relay 107 to ground. Relay 133 operates and in closing its alternate contacts connects ringing current to line L and thereby causes the operation of the ringing response relay 130.

135 through the tip and ring contacts of jack 127 and the plug 100. Relay 135 operates and locks in an obvious manner and in operating closes an obvious circuit to light the 5 supervisory lamp 136 indicating to the operator at office X that the line requires attention. After relay 135 operates relay 133 releases.

While the code of impulses was being transmitted office Y to office X, relay 316 10 was first operated and then released and while operated caused the energization of relay 318 in the same manner as described in connection with the relays 516 and 518, so 15 that when, at the termination of the call, the operator at office Y removes the plug 323 from the jack 324, the release control relay 321 is operated in the same manner that relay 521 was described as being operated, thus 20 grounding the conductors 312 and 315 to again initiate the operation of the sending mechanism SD³. The relay of this mechanism corresponding to relay 258 is operated upon the closure of the inner right-hand alternate contact of relay 321, so that the mechanism SD³ will transmit a series of 25 impulses similar to that sent by the sending mechanism of Fig. 2 when the operator at office X removed the plug 100 from jack 127. 30 The receiving mechanism RD³ responds to this code of impulses and transmits an impulse of positive polarity over conductor 152 which has no effect upon the relay 129 but causes the release of relay 128. 35 During the transmission of the code of impulses from office Y to office X which causes the release of relay 128, relays 316 to 319 function in the same manner as described in connection with the relays 516 and 519, 40 whereupon the mechanism at office Y is restored to normal, the busy signal magnets 320 and 520 having been released when relay 309 released in response to the removal of the plug 323 from the jack 324. 45 When the operator at office X removes plug 100 from the jack 127 the mechanism at said office is released in the same manner as described in connection with the mechanism of Fig. 7 when the plug 700 was removed from the jack 732.

From an understanding of the operation of establishing and releasing a connection between offices X and Y, it is believed that the completion and release of a connection initiated from office Z to office Y will be readily comprehended.

What is claimed is:

1. In a telephone system, terminating offices, an intermediate office, a plurality of 60 transmission lines interconnecting said offices, a signaling path common to said lines, busy signaling devices for each line at said offices, a line signaling device for each of said lines at said offices, means responsive to the initiation of a call at one of said of-

fices for transmitting impulses over said common path to the other offices, and means controlled by said impulses for operating a line signaling device at one of the latter offices and for operating busy signaling devices at 70 both offices.

2. In a telephone system, terminating offices, an intermediate office, a plurality of 75 transmission lines interconnecting said offices, a signaling path common to said lines, busy signaling devices for each line at said offices, a line signaling device for each of said lines at said offices, means responsive to the initiation of a call at one of said offices for transmitting impulses over said common path to the other offices, and means controlled by said impulses for operating the line signaling device at a terminating office and for operating the busy signaling devices at the intermediate office.

3. In a telephone system, terminating offices, an intermediate office, a plurality of 80 transmission lines interconnecting said offices, a signaling path common to said lines, busy signaling devices for each line at said offices, a line signaling device for each of said offices, means responsive to the initiation of a call at one of said offices for transmitting impulses over said common path to the other offices, and means controlled by 85 said impulses for operating a line signaling device at said intermediate office and for operating busy signaling devices at a terminating office.

4. In a telephone system, terminating offices, an intermediate office, a plurality of 90 transmission lines interconnecting said offices, a signaling path common to said lines, busy signaling devices for each line at said offices, a line signaling device for each of 95 said lines at said offices, means responsive to the initiation of a call at one of said offices for transmitting impulses over said common path to the other offices, and means controlled by said impulses for operating a line signaling device at a terminating office and for operating busy signaling devices at a terminating office.

5. In a telephone system, terminating offices, an intermediate office, a plurality of 100 transmission lines interconnecting said offices, a signaling path common to said lines, busy signaling devices for each line at said offices, a line signaling device for each of 105 said lines at said offices, means responsive to the initiation of a call at one of said offices for transmitting impulses over said common path to the other offices, and means controlled by said impulses for operating a line signaling device at a terminating office and for operating busy signaling devices at said terminating office and the intermediate office.

5. In a telephone system, terminating offices, an intermediate office, a plurality of 110 transmission lines interconnecting said offices, a signaling path common to said lines, busy signaling devices for each line at said offices, a line signaling device for each of 115 said lines at said offices, means responsive to the initiation of a call at one of said terminating offices for transmitting impulses over said common path to the other offices and means controlled by said impulses for operating a line signaling device at said intermediate office and for operating busy signaling devices at the latter office and at another terminating office.

6. In a telephone system, terminating 120

- offices, an intermediate office, a plurality of transmission lines interconnecting said offices, a signaling path common to said lines, busy signaling devices for each line at said offices, a plurality of line signaling devices at one office for each of said lines, means responsive to the seizure of one of said lines at one office for transmitting impulses over said common path to the other offices, means controlled by said impulses for operating the busy signaling devices at said other offices individual to the seized line, and means responsive to said impulses for operating one of the plurality of line signaling devices individual to the seized line. 70
7. In a telephone system, terminating offices, an intermediate office, a plurality of transmission lines interconnecting said offices, a signaling path common to said lines, busy signaling devices for each line at said offices, a line signaling device for each line at each terminating office, means responsive to the initiation of a call on one of said lines at one of said offices for transmitting impulses over said common path to the other offices, means at said intermediate office responsive to said impulses for operating the busy signaling devices of said line at said intermediate office, means for repeating said impulses at said intermediate office for transmission to a terminating office, and means at said terminating office responsive to the repeated impulses for operating thereat the line and busy signaling devices of said line. 85
8. In a telephone system, terminating offices, an intermediate office, a plurality of transmission lines interconnecting said offices, a signaling path common to said lines, busy signaling devices for each line at said offices, a line signaling device for each line at said offices, means responsive to the initiation of a call on one of said lines at one of said offices for transmitting impulses over said common path to the other offices, means at said intermediate office responsive to said impulses for operating thereat the line and busy signaling devices of said line, means for repeating said impulses for transmission to a terminating office, and means at said terminating office responsive to the repeated impulses for operating thereat the busy signaling devices of said line. 90
9. In a telephone system, distant offices, an intermediate office, a plurality of transmission lines interconnecting said offices, busy signaling devices for each of said lines at said intermediate office, a signaling path common to said lines, a plurality of line signaling devices at each distant office individual to each of said lines, means controlled at one distant office for transmitting over said signaling path a code of impulses individual to one of said lines and to one of the line signaling devices for said line, means at the intermediate office responsive to said 105
- code of impulses for operating the busy signaling devices individual to said line, and means at the other distant office responsive to said code of impulses for operating said line signaling device. 75
10. In a telephone system, distant offices, an intermediate office, a plurality of transmission lines interconnecting said offices, busy signaling devices for each of said lines at said intermediate office, a signaling path common to said lines, a plurality of line signaling devices at each distant office individual to each of said lines, means for transmitting over said signaling path codes of impulses individual to each line for operating said line signaling devices, selectively controlled means associated with the last named means and responsive to the initiation of a call on one of said lines to determine the characteristics of one of said codes of impulses individual to said line, means at the intermediate office responsive to a code of impulses for operating the busy signaling devices for said line, and means responsive to the transmission of said code for operating one of said line signaling devices. 80
11. In a telephone system, distant offices, a plurality of transmission lines interconnecting said offices, a signaling path common to said lines, a plurality of signaling devices at each office individual to each of said lines, a plurality of terminals individual to each line, means for transmitting over said signaling path codes of impulses individual to each line and to each of the terminals for said line for operating said signals, a plurality of selective switches associated with the last named means and responsive to the initiation of a call through one of the terminals of one of said lines to 100 select contacts individual to said line and to said terminal and thereby determine the characteristics of the code of impulses individual to said line and terminal, and means responsive to the transmission of said code for operating one of said signaling devices. 105
12. In a telephone system, distant offices, a plurality of transmission lines interconnecting said offices, a signaling path common to said lines, a plurality of terminals at one office for each of said lines, a plurality of signaling devices at the other office individual to each line, means for transmitting over said signaling path codes of impulses, a plurality of switches serving said lines and responsive to the seizure at the first named office of one of the terminals thereof individual to a line to engage the wipers of said switches with contacts thereof individual to said line, another switch thereupon operated to select a contact individual to the seized terminal and cooperating with one of the first named switches to determine the characteristics of one of the codes of impulses individual to said line, 110 115 120 125 130

- and means at said other office responsive to said code of impulses for operating one of said signaling devices.
13. In a telephone system, distant offices, a plurality of transmission lines interconnecting said offices, a signaling path common to said lines, a plurality of terminals at one office for each of said lines, a plurality of signaling devices at the other office individual to each line, each of said signaling devices being also individual to one of the terminals at the first named office, means for transmitting over said signaling path codes of impulses individual to each line, a plurality of switches serving said lines and responsive to the seizure of one of said terminals individual to a line to engage the wipers of said switches with contacts thereof individual to said line, another switch thereupon operated to select a contact individual to the seized terminal and cooperating with one of the first named switches to determine the characteristics of one of the codes of impulses individual to said line, and means at said other office responsive to said code of impulses for operating the signaling device thereat which is individual to the seized terminal at the first named office.
14. In a telephone system, distant offices, a group of transmission lines interconnecting said offices, a signaling path common to said lines, means for transmitting codes of impulses over said signaling path, a plurality of terminals at one office individual to each line of said group, a switch individual to corresponding terminals of the various lines of said group, another switch common to said group of lines and the terminals associated therewith, means operable upon the seizure of a terminal of one of said lines to actuate said switches to select said line and the seized terminal, the actuation of said switches determining the characteristics of a code of impulses individual to said line and the seized terminal, a plurality of signaling devices at the other office, and means responsive to the determined code of impulses for selectively operating one of said signaling devices.
15. In a telephone system, distant offices, a plurality of transmission lines interconnecting said offices, a signaling path common to said lines, means for transmitting codes of impulses over said signaling path, a plurality of terminals at one office, a signaling device at the other office individual to each terminal, a plurality of switches operable in response to the selection of one of said terminals for determining through the wipers of said switches the characteristics of the code of impulses to be transmitted over said signaling path, and means responsive to the transmitted code of impulses for operating the signaling device at said other office individual to the selected terminal.
16. In a telephone system, distant offices, a plurality of transmission lines interconnecting said offices, a signaling path common to said lines, means for transmitting codes of impulses over said signaling path, a plurality of terminals at one office, a signaling device at the other office individual to each terminal, a plurality of switches operable in response to the selection of one of said terminals for determining the characteristics of the code of impulses to be transmitted over said signaling path, means common to said terminals for controlling the operation of certain of said switches, means individual to the selected terminal and cooperating with said common means for controlling the operation of another of said switches, and means responsive to the transmitted code of impulses for operating a signaling device at said other office individual to the selected terminal.
17. In a telephone system, distant offices, a plurality of transmission lines interconnecting said offices, a signaling path common to said lines, a plurality of terminals for each line, a line signaling device for each terminal, a plurality of switches each of which is individual to certain of the terminals of said lines and common to all of said lines, another switch common to all of the terminals of said lines, means at one office responsive to the seizure of a terminal of one line for operating said switches, means for controlling the operation of said switches to determine the characteristics of a code of impulses to be transmitted over said common signaling path, and means at the other office responsive to said code of impulses for operating the line signaling device individual to the seized terminal.
18. In a telephone system, distant offices, a plurality of transmission lines interconnecting said offices, a signaling path common to said lines, a plurality of terminals for each line, a line signaling device for each terminal, a plurality of switches each individual to certain of the terminals of said lines and common to all of said lines; another switch common to all of the terminals of said lines, means at one office responsive to the seizure of a terminal of one line for operating the first named switches, means controlled by one of the latter switches thereupon operated to actuate said other switch to cooperate with said latter switch in determining the characteristics of a code of impulses to be transmitted over said signaling path, and means at the other office responsive to said code of impulses for operating the line signaling device individual to the seized terminal.
19. In a telephone system, a plurality of transmission lines extending from a station, a terminal at the station for each transmission line, another terminal at the station

- for each transmission line, a selective switch common to all transmission lines but individual to the first mentioned terminals thereof, another selective switch common to all terminals of all transmission lines and means for cooperatively actuating the switches to determine the characteristics of a code of impulses.
20. The method which comprises sending a code of impulses from one terminating office to an intermediate office, translating said code into a busy signal, repeating said code to another terminating office and translating said code at the last mentioned office into a calling signal.
21. The method which comprises sending a code of impulses from one terminating office to an intermediate office, translating said code into a calling signal, repeating said code to another terminating office and translating said code at the last mentioned office into a busy signal.
22. The method which comprises sending a code of impulses from one terminating office to an intermediate office, translating said code into busy and calling signals, repeating said code to another terminating office, and translating said code at the last mentioned office into a busy signal.
23. The method which comprises sending a code of impulses from one terminating office to an intermediate office, translating said code into a busy signal, repeating said code to another terminating office, and translating said code at the last mentioned office into calling and busy signals.
24. The method which comprises sending codes of impulses over a common signaling path from one terminating office to an intermediate office, translating each of said codes into a busy signal, repeating said codes to another terminating office, and translating each of said codes at the last mentioned office into a calling signal.
25. The method which comprises sending codes of impulses over a common signaling path from one terminating office to an intermediate office, translating each of said codes into a calling signal, repeating said codes to another terminating office, and translating each code at the last mentioned office into a busy signal.
26. The method which comprises cooperatively actuating a plurality of selective switches to determine the characteristics of a code of impulses, sending said code over a common signaling path, and translating said code of impulses into calling and busy signals.
27. In a telephone system, a transmission line extending from a station and terminating thereat in a plurality of terminals, a selective switch for said line, a selective switch for each of said terminals, and means effective subsequent to the seizure of said line by way of one of said terminals for cooperatively actuating said line switch and the corresponding terminal switch to determine the characteristics of a code of impulses.
28. In a telephone system, a transmission line extending from a station and terminating thereat in a plurality of terminals, other stations having busy signaling devices and line signaling devices individual to said line, selective switches, and means for setting said switches in a manner characteristic of the terminal employed in establishing a connection over said line for transmitting a code of impulses individual to said terminal whereby all of said busy signaling devices and a certain of said line signaling devices are actuated.
29. In a telephone system, first, second and third stations, a transmission line interconnecting said stations and terminating at said first station in a plurality of terminals, line signals at said second and third stations, busy signals at all of said stations, selective switches, and means for setting said switches in a manner characteristic of the terminal employed in establishing a connection over said line to transmit a code of impulses characteristic of the terminal employed whereby said busy signals and a certain of said line signals are operated.
- In witness whereof, I hereunto subscribe my name this 31st day of December A. D., 1921.

HUGH D. MACPHERSON.
